(57) **CLAIM**

The ornamental design for a motorcycle passenger backrest,
as shown and described.

DESCRIPTION

FIG. 1 is a perspective view of a motorcycle passenger
backrest showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines in the drawings depict portions of the
motorcycle passenger backrest that form no part of the
claimed design.
